UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

LINE-CASTING MACHINE.

1,077,642.

Specification of Letters Patent.

Patented Nov. 4, 1913.

Application filed January 16, 1911. Serial No. 602,865.

To all whom it may concern:

Be it known that I, JOHN R. ROGERS, a citizen of the United States, and a resident of the borough of Brooklyn, county of 5 Kings, and State of New York, have invented a new and useful Improvement in Line-Casting Machines, of which the following is a specification.

My invention has reference to line casting 10 machines of the Mergenthaler type, represented as to their general organization in Letters Patent of the United States Nos. 436,532 and 557,000. In these machines the circulating matrices are stored in an inclined 15 magazine, secured to a heavy base-frame, which is in turn mounted in the main-frame. This base-frame is sustained near its upper end by a horizontal rod or bar forming a part of the main-frame, and is supported 20 at the lower or front end by a fixed, vertically channelled face-plate, through which the matrices are delivered, or by an equivalent support.

When it is required to speedily change 25 the size or style of type characters produced by the machine the magazine may be removed and replaced by another containing matrices of a different font. This removal is effected by two attendants, one of 30 whom stands at the front of the machine and lifts the forward end of the magazine until it assumes a horizontal position, being sustained at the rear end by the rod above-mentioned. The two attendants, one at the 35 rear and the other at the front, slide the magazine backward over the bar until it is balanced thereon, after which the attendant at the front passes to the rear to assist his companion in lifting the magazine clear of 40 the machine.

The object of the present invention is to adapt machines of the above class, and more particularly the old machines already in existence, for a more speedy, easier and safer 45 removal of the magazine; and to this end it consists in combining with the main-frame and the magazine, means adapted to lift the forward end of the magazine clear of the parts at the front of the machine, and give 50 it support in such manner that it may be easily disengaged from the support at the rear, and drawn forward clear of the ma-

chine at the front without danger of canting or tipping sidewise.

The invention also consists in various details of construction hereinafter described.

With the exception of the parts specifically described herein the machine may be in all respects of the construction in the above-mentioned Letters Patent, or of the 60 construction embodied in commercial Mergenthaler linotype machines familiar to all persons skilled in the art.

In the drawings: Figure 1 is a perspective view, looking from the rear, of the 65 upper part of a Mergenthaler machine with my improvement embodied therein. Fig. 2 is a top plan view of the magazine. Fig. 3 is a vertical cross-section illustrating the manner in which the magazine receives support in its elevated position while being 70 withdrawn from or applied to the machine.

Referring to the drawings; A represents the main-frame, comprising, among other parts, the column a, the skeleton frame or 75 bracket a', secured to the column and extending laterally therefrom to support the matrix-distributing mechanism B, and the horizontal rod C, which latter sustains the upper rear end of the magazine. 80

D represents the magazine as a whole, comprising the magazine proper—consisting, as usual, of two parallel plates, d and d', spaced apart and provided with internal longitudinal channels to receive and guide 85 the edges of the matrices—and the rigid base-frame d², to which the magazine proper is secured, and by which the magazine is prevented from sagging or twisting out of form, as it would otherwise do, in consequence of the weight of the contained 90 matrices.

As shown in the drawings, the magazine when in operative position stands at an inclination, its upper rear end being rigidly 95 supported on the rod C, and its lower end sustained on the face-plate or forward portion of the main-frame.

In carrying my invention into effect I provide a support by which the forward 100 end of the magazine may be lifted and upheld clear of the face-plate and the other parts at the front of the machine, so that it may be safely and rapidly drawn forward

out of the machine, over the support as a fulcrum. This support may be constructed in various equivalent forms, as will appear to the skilled mechanic after reading this specification.

- 5 In the form shown the support consists of a horizontal roller or rod E, underlying the magazine near the forward end, and firmly attached to the arm or lever F, which is in turn secured to the shaft G, mounted in a rigid bracket or bearing H, which I secure to the main-frame. This shaft is provided with a lever I, extending rearward and downward in convenient reach of the attendant. The parts F, G and I form in effect a rigid or continuous member. When the magazine is to be removed the attendant depresses the rear end of the lever I, the effect of which is to lift the horizontal rod or support E, causing it to carry the forward end of the magazine upward, clear of the front parts of the machine, as shown in dotted lines in Fig. 1. After the magazine is thus lifted it is sustained in position by locking the lever. This may be effected by means of a pin J, adapted to enter a hole in the main-frame, behind the lever, or by any other suitable means. The effect is to sustain the magazine support E so that it in turn sustains or supports the magazine at a point midway of its length, or thereabout, the rear end resting for the time being on the fixed rod C. When the magazine is thus sustained the attendant, passing to the front 35 of the machine, and taking hold of the forward end of the magazine, is enabled to draw it forward and downward to such a position that it can be lifted clear of the machine. During this action the rear end 40 of the magazine slides upon and is sustained by the elevated rod E, which not only sustains a portion of the weight, but prevents the magazine from tipping or canting sideways.
- 45 If the magazine is made as usual, with rigid hooks or lugs at the upper end engaging behind the rod C, it may be canted on the rod E as a fulcrum to lift those hooks clear of the rod C before it is moved forward; but in order to avoid this canting or unlocking action I prefer to provide the magazine on each side with a long lever K, pivoted at k, and having its rear end bent downward or inclined over the rod C. By 50 depressing the forward ends of these levers their rear ends may be lifted and disengaged from the rod C, and the magazine permitted to slide directly forward on the rod or support E.
- 60 So far as described the magazine, except as to the levers K, is of the same construction as that commonly used in commercial Mergenthaler machines, and shown in Patent No. 436,582—the magazine with the 65 base-frame and the escapements which con-

trol the delivery of the matrices being removed as a unit.

When another magazine is to be applied the rod E is secured in the elevated position, the rear end of the magazine laid on this rod as a support, the magazine shoved upward and rearward to the limit, and the forward end dropped down to the operative position.

I represents a curved, channeled throat or entrance attached to the upper end of the magazine in position to receive the matrices falling from the distributor above. This throat, hinged to the magazine, may be retained, or a separate throat, otherwise supported, may be used, in a manner well understood in the art, this feature forming no part of my invention.

While I recommend the employment of the rod E and the lever supporting and sustaining the same, it is to be understood that any similar support adapted to lift and sustain the magazine as a whole, including the base-frame, may be employed.

I believe it to be wholly new in this class of machines to provide a support by which a magazine sustained at the rear may be lifted at the front and sustained for removal in a forward direction, the support being of such character as to admit of the magazine being drawn forward and canted 95 downward over it for removal at the front.

It is to be noted that in the construction herein shown the support E directly underlies the middle portion of the rigid base-frame of the magazine, so that although the heavy magazine is raised to such height and position that it cannot be withdrawn directly forward from the machine, it can be readily moved forward sufficiently to be balanced on the support, and then canted downward at the front and moved forward into such a position that it can be grasped and removed by the attendant, the support E serving during this action to sustain a portion of the weight and to prevent the magazine from coming in contact with the face-plate or forward parts of the machine.

A clear distinction is to be drawn between this support, terminating under the middle portion of the rigid magazine, and those flat supporting frames which are mounted rigidly in the main-frame and adapted to extend under the whole length of the magazine, for the purpose of giving the magazine proper rigidity when in action, and of sustaining it to the extreme front of the machine when it is being removed therefrom. The present construction is applicable, as before stated, to the magazines of the older type, with rigid base-frames.

Having described my invention, what I claim is:

1. In a line casting machine of the class described, the main-frame containing the rod C and the inclined magazine sustained

at its upper end on said rod, and relatively movable means connected to the magazine whereby the magazine may be disconnected from the rod at will, in combination with 5 means for lifting the forward end of the magazine and sustaining the same near the middle of its length, said means adapted to permit the magazine to be drawn forward and balanced thereover and removed at the 10 front of the machine.

2. In combination, the main frame having a rear magazine support, the inclined magazine removable therefrom in a forward direction, the rod E underlying the middle 15 portion of the magazine, lever connections for lifting the rod and upholding the same, and locking devices connected to the magazine and engaging the support, the said devices being movable relatively to the magazine 20 to disengage them from the support and permit the removal of the magazine.

3. In a machine of the class described the combination of the main frame, an inclined magazine with a rigid base-frame, and 25 a lifting and sustaining means directly underlying the middle portion of the magazine, said means adapted to permit the magazine to be drawn forward thereon and balanced 30 thereover for removal at the front of the machine, together with relatively movable means connected to the base frame whereby the magazine may be disengaged from the main frame at will.

4. In a machine of the class described, the 35 main frame, the inclined magazine mounted thereon and removable therefrom in a for-

ward direction, locking means carried by the magazine and engaging the main frame to support it in position thereon, and means for lifting and sustaining the magazine 40 without disengaging the locking means from the main frame, the said locking means being movable relatively to the magazine to disengage them from the main frame and permit the removal of the magazine. 45

5. In a machine of the class described, the main frame having a support for the rear end of the magazine, the inclined magazine removable therefrom in a forward direction, and locking devices carried by the magazine 50 and engaging the rear support, the said devices being movable relatively to the magazine to disengage them from the support and permit the removal of the magazine.

6. In a machine of the class described, the 55 combination of a magazine holder, a magazine mounted thereon in an inclined position and adapted to slide forwardly by gravity, and a locking device carried by the magazine and engaging the holder and serving to support the magazine against forward movement, said device being movable relatively to the magazine to disengage it from the holder and thus permit it to slide forwardly.

In testimony whereof I hereunto set my 60 hand this thirteenth day of January, 1911, in the presence of two attesting witnesses.

JOHN R. ROGERS.
